UNITED STATES PATENT OFFICE.

MURRY MILLER, OF NEW YORK, N. Y.

BAG LATCH.

Application filed February 8, 1927. Serial No. 166,759.

This invention relates to latches for hand bags, pocketbooks and similar articles, and refers more particularly to latches employed in conjunction with the frames of such articles.

The principal object of the present invention is the provision in a hand bag or similar article, of a strong, durable and practical means for releasably latching frame sections of the hand bag or similar article.

Another object of the invention is the provision of a latch which will be of dual character in that it will function as a snap fastener, as well as to effectively hold the frame sections of the hand bag against pulling and other forces and strains tending to move the frame sections to an opened relationship.

The nature of the invention and its distinguishing features and advantages will appear when the following specification is read in connection with the accompanying drawing, in which—

Figure 1 is an elevation looking down on a common type of hand bag embodying the latch of the present invention, the frame sections of the bag being held in a closed relationship by the latch.

Fig. 2 is a view similar to Fig. 1, showing the frame sections of the bag unlatched and in an opened relationship.

Fig. 3 is a side elevation of the bag and latch as shown in Fig. 1, a portion of the bag being broken away.

Fig. 4 is an elevation of the sliding element of bolt forming a part of the latch.

As stated, the latch of the present invention will be employed in conjunction with the frame of a hand bag, pocketbook or similar article. Therefore, in the drawing there has been illustrated a hand bag 10 having a frame consisting of two substantially similar sections 11 and 12 which are hingedly connected together at opposite sides as at 13. The receptacle body of the bag is connected in any preferred manner with the frame sections 11 and 12. The frame sections 11 and 12 are adapted to be moved to an opened and a closed relationship.

The latch of the present invention includes a tubular member 14 which is secured to the top of the frame section 11 in any suitable manner such as by soldering or riveting. The tubular member 14 is arranged at one side of the frame section 11. The tubular member 14 has an elongated slot 15 therein

which opens through the open end of the tubular member. The slot 15 terminates short of the opposite end of the tubular member 14, which is closed as at 16. A second tubular member 17 is provided, and is substantially similar to the tubular member 14 in that it is of the same diameter, and is approximately of the same length. The tubular member 17 is secured to the top of the frame section 12 in any suitable manner such as by soldering or riveting. The tubular member 17 has an L-shaped slot, the branch 18 of which opens through the open end of the tubular member, and the branch 19 of which extends circumferentially a short distance of the tubular member, thus providing a projection 20. The opposite end of the tubular member 17 is closed as at 21. When the frame sections 11 and 12 are brought to a closed relationship, the tubular members 14 and 17 will be in alignment as shown most clearly in Fig. 1, and the slots respectively in the tubular members will be in communication with each other. An element in the form of a bolt 22 is employed, the said bolt being slidably associated with the tubular members 14 and 17 to releasably hold the frame sections in a closed relationship. The bolt 22 has an apertured lug or eyelet 23 at one end. The lug or eyelet is adapted for connection with a pull tab 24. The bolt 22 is preferably inserted in the tubular member 17, and is of such length that when one end is in contact with the end wall 21, the opposite rounded end 25 will project slightly from the related end of the tubular member 17, as shown most clearly in Fig. 2. When the bolt 22 is moved into the tubular member 17 as far as it will go, the lug 23 may then be brought into the branch 19 of the L-shaped slot with the rounded end 25 projecting from the related end of the tubular member 17. The bolt 22 will be held against sliding movement in one direction by reason of the fact that the lug 23 will be confronted by the projection 20 and the bolt 22 will be held against sliding movement in the opposite direction by the opposite wall of the L-shaped slot.

Attention is now called to the fact that the frame sections 11 and 12 are permitted to have relative longitudinal movement to a slight degree by virtue of the flexibility of the members of the frame sections 11 and 12. Therefore, when the bolt 22 is slid home

2

in the tubular member 17 with the lug 23 in the branch 19 of the L-shaped slot, it is possible to either move the frame sections 11 and 12 to a closed relationship or to an 5 opened relationship. These performances are accompanied by a coaction of the rounded end 25 with the edge 26 of the tubular member 14. The effect obtained is similar to that obtained with a snap fastener. 10 When the frame sections 11 and 12 are brought to a closed relationship, the said sections will move longitudinally slightly with respect to each other, due to the coaction of the rounded end 25 with the edge 15 26, and said rounded end 25 will project into the adjacent end of the tubular member 17. The frame sections 11 and 12 will thus be releasably held in a closed relationship. The frame section 11 has connected there- 20 with a loop 27. By taking hold of the loop 27 with one hand, and the tab 24 with the other hand, the necessary pulling force may be exerted to move the frame sections 11 and 12 to the opened relationship. A pull 25 on the tab 24 would effect the opened relationship of the frame sections 11 and 12, will always insure the lug 22 being in the branch 19 of the L-shaped slot, and the bolt 22 will therefore be held against unintentional slid- 30 ing movement out of the tubular member 17.

In order to effectively hold the frame sections 11 and 12 in a closed relationship, the bolt 22 may be slid to extend into the tubular member 14. This is accomplished after the 35 frame sections 11 and 12 have been brought together, whereupon the lug 23 is moved from the branch 19 of the L-shaped slot to a position in which it may slide from the branch 18 of the L-shaped slot into the slot 40 15 in the tubular member 14. The bolt 22 may be slid by exerting a pull on the tab 24 until the lug 23 engages the end wall of the slot 15, thus limiting sliding movement of the bolt 22 to a position in which the oppo- 45 site end thereof, because of the length of the bolt will extend into the tubular member 17. It will therefore be understood that it is possible to hold the frame sections 11 and 12 in a closed relationship against 50 unintentional pulling and other forces and strains tending to move the frame sections to an opened relationship.

It is to be understood that the invention is not restricted to the precise arrangement 55 of parts shown and described, as details of construction may be modified and rearranged without departing from the spirit of the invention, the scope of which is limited only by the terms of the appended claims.

60 I claim:

1. The combination with a bag frame consisting of hingedly connected sections, of a latch consisting of a bolt movably associated with two tubular members respectively carried by said hingedly connected sections,

and said bolt having means movable into and out of slots respectively in said tubular members for effecting the movement of said bolt, so as to latch and unlatch the sections of said bag frame. 70

2. The combination with a bag frame consisting of hingedly connected sections, of a latch consisting of a bolt slidably and turnably associated with two tubular members respectively carried by said hingedly connected sections, and said bolt having means movable into and out of slots respectively in said tubular members for effecting the sliding and turning movement of said bolt, so as to latch and unlatch the sections of said 75 bag frame. 80

3. The combination with a bag frame consisting of hingedly connected sections, of a latch consisting of a bolt slidably associated with two tubular members respectively carried by said hingedly connected sections, and the bolt being of a length to extend into both of said tubular members to latch said frame sections in a closed relationship in one position of said bolt, sub- 85 ject to movement to an opened relationship by the exertion of a pulling force applied to effect the movement of the frame sections to the open relationship, and said bolt being slidable to another position so that one end thereof will act in conjunction with the tubular members to hold said frame sections latched in a closed relationship against a pulling force applied to effect the movement of the frame sections to the opened relationship. 90

4. The combination with a bag frame consisting of hingedly connected sections, of a latch consisting of a bolt slidably associated with two tubular members respectively carried by said hingedly connected sections, one end of the bolt adapted to coact with one end of one of said tubular members when the bolt is in one position, the frame sections 100 capable of being sprung apart in the coaction of the bolt with the end of the tubular member, said bolt end and the end of the tubular member serving to releasably hold the frame sections in a closed relationship, and subject to a pulling force for effecting 105 the movement of the frame sections to an opened relationship. 110

5. The combination with a bag frame consisting of hingedly connected sections, of tubular members respectively secured to said sections, an element slidably associated with said tubular members, one of said tubular members having an elongated slot opening through one end thereof, the other tubular member having an L-shaped slot opening 120 through one end thereof, one slot connecting with the other slot when the tubular members are in alignment, a tab lug on one end of the element, the lug coacting with the end wall of the elongated slot to limit the 125 130

movement of said element in one direction, said lug also capable of coacting with the walls of the L-shaped slot to prevent the sliding movement of the element.

5 6. The combination with a bag frame consisting of hingedly connected sections, of means coacting with the frame sections to releasably latch the frame sections in a closed relationship subject to movement to 10 an opened relationship by the exertion of a pulling force applied to effect the movement of the frame sections to the opened relationship, said means also serving to positively latch the frame sections in the closed 15 relationship against a pulling force applied to effect the movement of the frame sections to the opened relationship.

7. In a bag, frame sections hingedly connected together, latch elements respectively 20 on the frame sections, the contiguous ends of said latch elements being adapted to have

frictional latching engagement in the closed relationship of said frame sections, and fastener means on said frame sections additional to said latch elements and movable 25 into and out of fastening position to positively fasten the frame sections and latch elements, in the closed position of the frame sections.

8. In a bag, frame sections hingedly connected together, latch elements respectively on the frame sections, the contiguous ends of said latch elements being adapted to have frictional latching engagement in the closed relationship of said frame sections, and fastener means additional to said latch elements, said fastener means slidably supported on one frame section and movable 30 into and out of fastening relation to the latch element carried by the other frame 35 section.

MURRY MILLER.
